(57) **CLAIM**

We claim the ornamental design for an analyte test meter in a docking station, as shown and described.

DESCRIPTION

FIG. 1 is a top, front and right side perspective view of an analyte test meter in a docking station;

FIG. 2 is a top, rear and left side perspective view thereof;

FIG. 3 is a rear elevational view thereof;

FIG. 4 is a front elevational view thereof;

FIG. 5 is a rear elevational view thereof;

FIG. 6 is a bottom plan view thereof;

FIG. 7 is a left side elevational view thereof; and,

FIG. 8 is a right side elevational view thereof.
